UNITED STATES PATENT OFFICE.

JACOB EHRAT, OF ZURICH, SWITZERLAND.

DEVICE FOR INCREASING THE EFFICIENCY OF INTERNAL-COMBUSTION ENGINES.

1,413,711.

Specification of Letters Patent. Patented Apr. 25, 1922.

Application filed March 15, 1921. Serial No. 452,623.

To all whom it may concern:

Be it known that I, JACOB EHRAT, a citizen of the Republic of Switzerland, and resident of Zurich, in the Canton of Zurich, 5 Switzerland, have invented certain new and useful Improvements in Devices for Increasing the Efficiency of Internal-Combustion Engines, of which the following is a clear and full specification, reference being had 10 to the accompanying drawings, in which—

Fig. 1 shows a vertical section through the device;

Fig. 2 shows a sectional elevation of a portion of the device, taken at right angles to 15 that shown in Fig. 1, and

Figs. 3 and 4 represent a sectional view and a plan, respectively, of details.

Referring in detail to these drawings, 1 designates the engine cylinder and 2 a lining 20 of steel fitted therein. The cylinder is surrounded by and made integral with a cylindrical casing 3 and forms therewith a water-jacket 4 of ring-shaped section serving for the cooling of the cylinder in the usual and known manner. Mounted at the 25 top of the lining 2 is an interchangeable shielding member 5 which at its upper side is provided with a cup-shaped central portion and a circular groove 6, and at the circumference with a shoulder to serve as a rest for a supporting ring 7 of which the inner face is spherical. The ring 7 and the member 5 thus form together a bearing for a semi-spherical oscillating valve 8. The supporting ring 7 is provided with two oppositely disposed openings 9 and 9' of which one serves as an inlet for the mixture of gas entering from the suction chamber 10, while the other opening allows the exhaust gases 35 to be discharged from the explosion chamber 40 to be discharged from the explosion chamber into the exhaust channel 11. A recess machined in the top part of the supporting ring 7 permits the mounting therein of the oscillating valve 8, the said ring moreover 45 having four small slots 12, 12' and 12^a, 12^b, their purpose being hereinafter described. The oscillating valve has fashioned therein, at diametrically opposite places, two V-shaped apertures 13 the tapered ends thereof 50 terminating in a circular opening 13' and giving a certain resiliency to the said valve. The latter possesses furthermore two oppositely arranged integral extensions 14 serving as bearings and pivots for the rotary 55 movement of the valve. A spherical knob 15 secured at the top of the oscillating valve

is made to engage with an opening provided in the middle part of a rod 16 forming a member of the valve controlling gear, the said knob being adapted to be gripped and held by means of a slideable jaw 17 which, in turn, is under the control of an adjusting screw 18 extending through one end of the rod 16. The rod 16 is journalled in sleeves 19 fitted in the top portion of the engine cylinder and made slideable therein in an axial direction. The end of the rod 16 carrying the adjusting screw 18 is covered and protected by a casing 20, and the other end of such rod carries a ring 21 having a convex 65 outer face and adapted to be held in position by an adjusting nut 22. Linked to the ring 21 is one arm of a lever 23 pivoted to the engine casing at 24, the means for imparting a swinging movement to this lever 70 being of the known type and therefore not illustrated.

Mounted in a housing located above the oscillating valve and formed by a cylindrical wall 25 is an auxiliary carbureter. 80 The wall 25 in its lower part is surrounded by a cooling-water jacket 26 and the top part carries a cover 27 having a central hollow portion 28 which is cylindrical and projects downwardly thus forming with said wall a 85 chamber 29. The cover portion 28 is provided upon its circumference with integral ring-shaped protecting ribs or flanges 30 situated at equal distances from each other, and near its top there are a series of openings 31. A second cover 32 is adapted to close the hollow portion 28 of the first cover, while a fuel supply pipe 33 extends through the former and ends in a flange 35 having a central bore 34 terminating in a semi-spherical recess 36. A float needle-valve 37 in turn extends through the fuel supply pipe and carries at its lower end a ball 38 of a size corresponding with that of the recess 36 and therefore adapted to close the same. 90 The fuel supply pipe 33 consists of an inner and an outer tube which are integral with the aforesaid second cover 32 and consequently form a chamber 39 which, by means of lateral apertures 40 disposed near its top, 95 is caused to communicate with the atmosphere for cooling purposes. A float 41 of ring-shaped section is mounted between the wall forming the cover portion 28 and the outer tube of the fuel supply pipe, this float 100 having a bridge-piece 42 at its base which bridge-piece itself is provided with a recess 105

43 corresponding with and designed to receive the ball 38. An opening located at 44 in the cover 27 serves as a means to mount a safety valve with manometer connections (not shown). Z designates the ignition plug.

5 In action the device described operates in the following manner.

Assuming that the several parts comprising the device are in the position shown in 10 Fig. 1 and that the lever 23 is continuously acted upon by some suitable mechanism and source of power (not shown), the rod 16 is caused to be moved to and fro in the direction of the arrows, Fig. 1. On the movement of the rod 16 to the right the oscillating valve 8 is made to turn far enough to cause the opening 9 in the supporting ring 7 to be freed thereby allowing the mixture of gases to enter from the suction chamber 10 into the explosion chamber. The turning movement of the valve 8 into the position described has at the same time the effect of bringing the apertures 13 of the oscillating valve into line with the slots 12', 12'' in the 15 supporting ring 7. Upon the return of the rod 16 into the position according to Fig. 1 the mixture of gases now in the explosion chamber is ignited by the ignition plug Z and made to explode. Thereafter the rod 20 16, owing to the action of the lever 23, is moved to the left whereby the oscillating valve frees the opening 9' in the supporting ring 7 and allows communication of such opening with the correspondingly situated 25 exhaust channel 11. In this latter position of the oscillating valve the slots 12, 12' in the ring 7 correspond with the apertures 13 in the said valve, a portion of the exhaust gases being then able to enter into the chamber 29 of the auxiliary carbureter. The 30 liquid fuel contained in the hollow cover portion 28 is thereby heated and reduced to gas which flows out through the openings 31 into the chamber 29. Thence the gases, when 35 the oscillating valve 8 is in a corresponding position, that is, when it uncovers the openings 9 and 12', 12'' in the ring 7, can enter into the explosion chamber and there mix with the fuel coming from the main carbureter so that by the subsequent explosion 40 the efficiency of the engine is increased.

50 The fuel supply to the auxiliary carbureter is regulated by means of the float 41, the bridge-piece 42 thereof acting on the ball 38 carried by the needle-valve 37. The ball 38, as soon as the fuel in the hollow cover portion 28 has reached a certain level, then closes the recess 35 and the bore 34 in the supply pipe 33.

60 The gaseous fuel entering from the auxiliary carbureter into the explosion chamber is caused to mix in the latter with the fuel supplied from the main carbureter, which has the great advantage that the formation 65 of sediments and cleavages are prevented,

The device as hereinbefore set forth permits of a perfect combustion of the fuel which fact, besides economical advantages, has the further advantage that the exhaust gases are free from the otherwise nasty 70 odours.

The construction of the oscillating valve and the supporting ring possesses furthermore the advantage that upon the movement of the valve in one direction the inlet 75 for the fuel relative to the main and the auxiliary carbureters is opened simultaneously, while the movement of the valve in the other direction similarly causes the outlet for the exhaust gases to be opened to 80 the auxiliary carbureter and at the same time to the exhaust channel 11.

The purpose and effect of the shielding member 5 is that the oscillating valve is prevented from being unduly influenced 85 either by pressure or heat coming from the explosion chamber. Again, owing to a certain amount of resiliency of parts of the oscillating valve it may expand during its operation without danger of over-stress. 90

And since the main and auxiliary carbureters are fed by two independent fuel containers, it is possible to use fuels of different gravity. Heavy hydrogen-gases may for instance be used and supplied to the 95 motor by the aid of the auxiliary carbureter.

The device described, as already mentioned, has for its main purpose to increase the efficiency of internal combustion engines, a feature of especial importance in 100 connection with motors for air craft.

Inasmuch as it is possible to apply to every engine cylinder a separate auxiliary carbureter, a fine and thorough spraying of the fuel is obtained and therefore highest 105 economy in the working of the motor realized. Another considerable advantage of my device consists in its great simplicity of construction, the latter consequently ensuring safe working and lasting of the operating parts. 110

Having now fully described my said invention what I claim and desire to secure by Letters Patent is:—

1. In a device for increasing the efficiency 115 of internal combustion engines, the combination with the engine cylinder having a cylindrical housing at its top, of an auxiliary carbureter mounted in the housing, an oscillating valve arranged between the said 120 housing and the explosion chamber of the engine cylinder, and means to actuate the said valve and regulate the supply of fuel to the auxiliary carbureter.

2. In a device for increasing the efficiency 125 of internal combustion engines, the combination, with the engine cylinder having a lining of steel fitted therein and a cylindrical housing at the top, of an auxiliary carbureter mounted in the housing, an oscillat- 130

ing valve arranged between the said housing and the explosion chamber of the engine cylinder, an interchangeable shielding member mounted and resting on the steel

5 lining and adapted to guide and protect the oscillating valve and means to actuate the said valve and regulate the supply of fuel to the auxiliary carbureter.

3. In the herein-described device for increasing the efficiency of internal combustion engines, the combination, with the engine cylinder having a cylindrical housing at the top, of an auxiliary carbureter mounted in the housing, an oscillating and semi-
10 spherical valve arranged between the said housing and the explosion chamber of the engine cylinder and having two oppositely disposed V-shaped apertures terminating in a circular opening, an interchangeable
15 shielding member fitted in the cylinder and adapted to guide and protect the oscillating valve, a supporting ring adjacent to and resting on the outside of the said shielding member, the said supporting ring assisting
20 in guiding the valve and being provided with two oppositely arranged openings and four slots serving as gas inlets and exhaust outlets respectively, and means to actuate the oscillating valve, all substantially as
25 30 and for the purpose set forth.

4. The combination, in the herein-de-

scribed device for increasing the efficiency of internal combustion engines, of an engine cylinder having a cylindrical housing at its top and a main carbureter, a steel lining fitted within the cylinder, an auxiliary carbureter of the float type mounted in said housing, a semi-spherical fuel controlling oscillating valve arranged between the casting and the explosion chamber of the engine cylinder, a shielding member mounted on said steel lining and adapted to guide the oscillating valve, a supporting ring adjacent to the shielding member to assist in guiding the said valve and having fuel inlets and exhaust outlets which are controlled by the oscillating valve, and means to actuate the latter, the said means comprising a spherical knob secured at the top of the oscillating valve, a horizontally disposed rod journaled in the top portion of the engine cylinder and having an opening with which the said knob engages, and mechanism to cause the movement to and fro of the said rod in an axial direction.

In testimony whereof I have hereunto set my hand in the presence of two subscribing witnesses.

JACOB EHRAT.
